Des 16 11

George Taylor and James Lusty of Amesbury, Mass.
Letters Patent No. 1611 dated July 1, 1802,

The schedule referred to in these Letters Patent and making part of the same,
To all whom it may concern,

Be it known that we George Taylor and James

Dec 16 11

Dusty, both of Amesbury in the County of Essex and State of Massachusetts have produced a new and ornamental design for Shoes, and we do hereby declare that the following is a full, clear, and exact description of the same reference being had to the accompanying drawing forming a part of this specification, in which -

Figure 1, represents a side elevation of one of our shoes.

Figure 2, is a plan or top view of the same.

Figure 3, is a detached plan view of the design for ornamenting the heels.

Similar letters in the several Figures indicate corresponding parts.

This design consists in an open flower attached to the front or toe part of the shoe, formed as hereinafter described with a bud and a leaf emanating on opposite sides from its stem, and in two tendrils with a series of flowers and leaves attached to the heel of the shoe; said tendrils being laid together so as to form a series of oblong rings of gradually decreasing size from the centre towards the ends.

To enable those skilled in the art to make and use our invention, we will proceed to describe it with reference to the drawing.

The front or toe part of the shoe A, is ornamented by a flower a, in full blossom consisting of one circular central leaf a', and seven leaves a² surrounding the inner circular leaf, said leaves being surrounded and intermingled with strips b, as clearly shown in Figure 2.

This flower is connected with a stem b, and from this stem a flower bud c emanates on one side, and a leaf d, on the other. The flower, the stem, the bud, and the leaf are made in appropriate colors, according to the materials from which the shoes are manufactured. The flower extends nearly down to the front end of the shoe and the inner end of the stem comes within a short distance of the instep.

The heel of the shoe is ornamented by two tendrils e, each of which is ornamented by a series of flowers f, f¹, f², f³, and leaves g, g¹, g², g³, and which are laid on, or interwoven with each other, so as to form a series of oblong rings h, h¹, h², h³. The tendrils are thickest in the middle and they come down to their points at both ends and the flowers and leaves are

3

Dec. 16/11

arranged partly inside the ring h, and partly outside as clearly shown in Figure 3. The middle ring which encircles the rear portion of the heel, is the largest, and said rings gradually decrease in size from the middle towards the points. The central ring h is ornamented by two flowers f, projecting from the tendrils towards the inside of the ring, and by a number of leaves g, partly on the inside of the ring, and partly on its outside, and partly on the stems of the flowers, as clearly shown in Figure 3. The rings h', adjoining the ring h, are ornamented each with three flowers f', and leaves g', two of said flowers being on the exterior and one on the interior of each ring. The remaining rings h² h³, are ornamented with two flowers f², and f³, and with leaves g² g³. The tendrils leaves and flowers are made in appropriate colors to suit the color of the material from which the shoes are manufactured.

Having thus fully described our design, what we claim as new and desire to secure by Letters Patent, is—

A shoe A, ornamented with a flower a, stem b, bud c, and leaf d, all as specified on the front or toe part; also the tendrils e, forming rings h, h', h², h³, and ornamented with flowers f, f', f², f³, and leaves g, g', g², g³, on the heel, all as shown and described.
